UNITED STATES PATENT OFFICE

146,950

DESIGN FOR A PIN OR SIMILAR ARTICLE

Murray Slater, Brooklyn, N. Y.

Application June 14, 1946, Serial No. 130,711

Term of patent 3½ years

(Cl. D45—19)

To all whom it may concern:

Be it known that I, Murray Slater, a citizen of the United States, residing at Brooklyn, in the county of Kings and State of New York, have invented a new, original, and ornamental Design for a Pin or Similar Article, of which the following is a specification, reference being had to the accompanying drawing, forming part thereof.

Fig. 1 is a front elevational view of a pin showing my new design with the dagger and sheath elements in a separated position;

Fig. 2 is a rear elevational view thereof with the elements in assembled position and with the chain broken away for purposes of illustration;

Fig. 3 is a front elevational view of the pin as shown in Fig. 2.

I claim:

The ornamental design for a pin or similar article, as shown and described.

MURRAY SLATER.
